UNITED STATES PATENT OFFICE.

CHARLES D. MURPHY, OF KINGSTON, MINNESOTA.

HORSESHOE.

No. 831,975.

Specification of Letters Patent.

Patented Sept. 25, 1906.

Application filed May 16, 1905. Serial No. 260,699.

To all whom it may concern:

Be it known that I, CHARLES D. MURPHY, a citizen of the United States, residing at Kingston, in the county of Meeker and State of Minnesota, have invented certain new and useful Improvements in Horseshoes, of which the following is a specification.

My invention relates to soft-tread horseshoes, and more particularly to those having the heel-calks actuated by a spring or similar device to cushion the same, and thus take up shock and the like.

A further object is to so construct the device that it can be easily and cheaply manufactured and the parts thereof removed and replaced when wear and repair require the same.

In the drawings forming a part of this specification, and in which like symbols of reference represent corresponding parts in the several views, Figure 1 is a side view of the device; Fig. 2, a bottom plan of the same. Fig. 3 is a rear view. Fig. 4 is a perspective view of the heel portion of the shoe upon which the spring operates, and Fig. 5 is a perspective view of the spring portion detached.

1 designates the horseshoe; 2, the toe-calk of same; 3, the spring-plates; 4, the heel portions of shoe; 5, screws, rivets, or the like connecting the springs 3 to the shoe; and 6, support and guide for heel-calks.

7 and 8 are lugs on shoe adapted to receive and limit arm 9; 10 and 11, recesses in shoe to receive the rear end of spring-carried piece 13 to give additional strength and resiliency to same; 5^a, screws connecting piece 13 to 3, and 12 represents screws or the like securing piece 9 to portion 13.

14 represents rear of section 13, adapted to be received in recesses 10 and 11, so as to give support and strength, as described, and 15 a modification of spring, which may be substituted for or used in conjunction with the spring shown.

45 The operation of my device will be apparent from the foregoing. The rear end of piece 13 is first placed in grooves or recesses 10 and 11 and connected to spring 13 by means of screws or the like, and said spring

is in turn connected to the shoe by screws. 50 The arm 9 is then placed in position so as to play between the lugs 7 and 8, and the device is ready for use. The arm 9 is made detachable, so that it may be renewed, if needed, same as other portions. The arm 55 9, portion 13, and piece 3 may, if desired, be made in one piece and connected by rivets to shoe in place of screws, as the heads of screws sometimes become weak under hard work.

Having now fully described my invention, 60 what I claim as new, and desire to secure by Letters Patent, is—

1. In a horseshoe, a resiliently-supported tread for the same, a post on the shoe having a reduced portion so as to form stops at its 65 top and bottom, and an arm on the tread, said arm carrying a lug which is adapted to play between the stops on the post.

2. In a horseshoe, a tread therefor, a recess in the shoe to receive the front of the tread, a 70 post or lug on the rear of the shoe having a cut-away portion so as to form stops at its top and bottom, and an arm on the tread adapted to be guided and controlled by the stops on the post.

3. In a soft-tread horseshoe, a cut-away portion on the shoe, a tread having its front portion supported over the same, a post on the cut-away portion having lugs at its top and bottom, and an arm on the tread adapted to ride between the lugs on the post to guide the tread.

4. In a horseshoe, reduced portions on the heels of the same, recesses formed in the heels of the shoe and leading into the reduced portions, treads yieldingly supported above and having their front portions resting in the recesses, lugs on the reduced portions having stops at top and bottom, arms connected with the treads and playing between the stops, 85 and a cut-away portion in the treads within which the lugs play.

In testimony whereof I affix my signature in presence of two witnesses.

CHARLES D. MURPHY.

Witnesses:

WILLIAM MURPHY,
Wm. CLARQUIST.
